DISPLAY RACK

Frederick A. Sunderhauf, Rutherford, N. J., assignor to Reynolds Metals Company, New York, N. Y., a corporation of Delaware.

Application April 28, 1936, Serial No. 76,732

2 Claims. (Cl. 248—198)

The invention relates to display racks. The object of the present invention is to provide a collapsible display rack constructed from a single flat piece of stock by a simple die cutting and die scoring process and designed for use on counters, show cases and similar places for displaying in retail stores small articles such as razor blade packages, packages of adhesive tape and other merchandise and adapted when collapsed to be shipped and stored flat and capable of being easily and quickly set up for use.

A further object of the invention is to provide a display rack of this character which will present an ornamental and attractive easel effect in displaying merchandise and which will enable the displayed goods to be readily inspected and easily removed by the purchaser when a sale is made.

Another object of the invention is to provide a display rack in which the means for supporting the displayed articles will when empty be of an ornamental character and enhance the attractiveness of the display rack.

With these and other objects in view, the invention consists in the construction and novel combination and arrangement of parts herein-after fully described, illustrated in the accompanying drawing and pointed out in the claims hereto appended, it being understood that various changes in the form, proportion and details of construction, within the scope of the claims, may be resorted to without departing from the spirit or sacrificing any of the advantages of the invention.

In the drawing:—

Fig. 1 is a rear perspective view of a display rack constructed in accordance with this invention and arranged for use, the display rack being provided with tabs for supporting and displaying razor blade packages.

Fig. 2 is a central vertical sectional view of the same.

Fig. 3 is a horizontal sectional view taken substantially on the line 3—3 of Fig. 2.

Fig. 4 is a plan view of the blank from which the display rack is formed.

Fig. 5 is a detail sectional view of a portion of the front member and bottom connecting member of the display rack showing the parts on an enlarged scale to illustrate the construction of the laminated die cut and die scored stock the parts being arranged at right angles for convenience of illustration.

Fig. 6 is a detail rear elevation of a portion of the display rack showing the interlocking con-

nection between the rear support and the bottom connecting member or base.

Fig. 7 is a front perspective view of a display rack provided with circular openings for the display of packages of adhesive tape or other merchandise.

Fig. 8 is a plan view of the blank from which the display rack shown in Fig. 7 is formed.

Referring particularly to Figs. 1 to 6, inclusive, of the drawing in which is illustrated a display rack provided with means for displaying razor blade packages, the display rack comprises in its construction an inclined front member 1, a rear inclined support 2 and a bottom connecting member 3 constituting a base for the display rack and hinged at its front portion to the inclined front member and extending rearwardly therefrom and detachably interlocked with the inclined support when the display rack is set up for use. The display rack is constructed from a single piece of flat material and is die cut to form a substantially oblong blank 4 which is scored at 5 and die cut at 6 to form the rear support 2. The rear support 2 is approximately U-shaped and is composed of spaced parallel sides 7 and a bottom connecting portion 8 which is provided with a central rectangular recess 9 adapted to be engaged by an approximately T-shaped head 10 of the body member 3.

The scoring 5 hinges the sides 7 of the rear support to the front member at opposite sides of the upper portion thereof and the support 2 is adapted to be arranged at an angle to the inclined front member to form a brace or prop for supporting the front member in an inclined position for use. The die cut 6 completely severs the inner edges of the support 2 from the front member and enables the support to swing on the hinge connections formed by the scoring 5.

The blank 4 is scored at 10a to form a hinge connection between the bottom connecting member 3 and the lower edge of the inclined front member 1 to enable the connecting member 3 to be swung rearwardly to form a base and a connecting element for retaining the inclined support in its supporting position. The blank is die cut to form the T-shaped head 10 and is preferably provided opposite the arms 11 of the head with recesses 12 forming arcuate edges and adapted to slightly enlarge the space between the arms 11 and the body portion of the bottom connecting member 3.

The straight sides 7 and the connecting bottom portion 8 of the rear support provides an

open space or opening through which the head 10 is adapted to extend to enable the neck portion 13 of the T-shaped head to drop into the recess 9 with the arms 11 of the T-shaped head in engagement with the rear support.

The U-shaped rear support while shown with straight sides and a straight connecting bottom portion may be of any other desired form and the blank 4 is preferably made of laminated stock 10 of board 14 and metal foil 15, as clearly illustrated in Fig. 5 of the drawing. The foil provides for attractiveness of the display and the backing of card or other board prevents tearing or mutilation of the metal foil during shipment and at 15 the same time the laminated structure provides a resilient joint or connection between the front member and the bottom member, the spring action of which resilient connection is adapted to cause the T-shaped head of the bottom connecting member to snap into engagement with the recess 9 of the support when the T-shaped head is placed over the recess 9 and is released.

When the T-shaped head of the bottom connecting member is in engagement with the recess 25 of the rear support the latter is securely retained in its supporting position and the said detachable connection enables the display stand to be easily and quickly set up for use or arranged in a flat condition for storing or shipping. The large 30 open space between the sides 1 of the support 2 greatly facilitates the setting up of the display rack for use as the said space provides ample room for the convenient handling of the connecting member 3 and the placing of the connecting member and the support in proper position 35 for their interlocking engagement.

In the form of the invention illustrated in Figs. 1 to 6, inclusive, of the drawing, the front member is provided with a horizontal row of approximately vertical tabs 15. The blank 4 is die cut at 16 and may or may not be die scored at 17 to form the horizontal row of vertical tabs 15 and a row of horizontal tabs 18 is preferably provided below the vertically exposed tabs 15 by die cutting the blank at 19. The blank may or may not be scored at 20 at one end of the horizontal tabs 18 which are provided more for ornamental purposes. The vertically disposed tabs 15 of the top row are designed for displaying razor blade packages which may be slipped over the tabs but the said tabs 15 may be employed for displaying various other packages of merchandise or small articles. The display stand provides ample space above the rows of tabs for advertising matter and it presents an ornamental appearance and it will be seen that the cutting of the substantially U-shaped support from the upper portion of the front member materially contributes to the ornamental character and attractiveness of the display rack. The material 50 cut to form the recess of the rear support provides a central projecting portion at the top of the front member and adds to the ornamental character of the display rack. The tabs 15 and 18 have rounded free ends and the openings 21 and 22 formed in the front member by the cutting of the tabs adds to the attractiveness of the display rack.

In Figs. 7 and 8 of the drawing is illustrated 70 another form of the invention in which the front member 23 is provided with rows of circular openings 24 for holding circular packages of adhesive tape or other articles of a similar shape

which may be readily placed in and removed from the openings 24. The display rack shown in Figs. 7 and 8 is constructed substantially the same as that illustrated in Figs. 1 to 6, inclusive, and is formed from a single piece rectangular blank 25 and comprises the said front member 23, a rear support 26 and a bottom connecting member 27 which is provided with a T-shaped head 28 for engaging the recess 29 of the support 26. The blank is die scored and cut substantially the same 10 as the blank 4 with the exception that the circular openings 24 are provided in place of the tabs 15 and 18 and the recesses adjacent the arms 30 of the T-shaped head 28 provide substantially straight angularly disposed edges 31. 15 While tabs and circular openings are shown for supporting the articles to be displayed it will be clear that any other equivalent means may be provided for mounting such merchandise on the display card formed by the inclined front 20 member.

What is claimed is:—

1. A compact display rack formed of a single generally rectangular-shaped blank die-cut and die-scored into three complementary sections 25 adapted to be folded into a generally triangular form comprising a front or display panel section formed intermediate the other two sections, an adjacent U-shaped rear panel section hinged by the ends of the U to said front panel intermediate 30 the top and bottom of said front panel and having a horizontal bottom edge equivalent to the width of the display rack and adapted throughout its entire length to contact a display counter, said front panel having a substantial 35 portion die-cut from stock originally lying within the U and a connective base panel section for connecting said front and rear sections, said sections being hinged together and separated by die-scoring and die-cutting without substantial loss 40 of material from the blank, said rear panel section being provided with a locking recess formed in the bottom of the U and said display panel section being provided with an ornamental projection corresponding in shape to said locking 45 recess, and a locking projection upon said base section adapted to fold into said locking recess in the said rear section to lock the rack in display position.

2. A compact display rack formed of a single generally rectangular shaped blank die-cut and die-scored into three complementary sections adapted to be folded into a generally triangular form comprising a front or display panel section formed intermediate the other two sections, an adjacent U-shaped rear panel section hinged by the ends of the U to said front panel intermediate 55 the top and bottom edges of said front panel, said front panel having a substantial area of stock originally lying within the U, and a connective base panel section for connecting said front and rear sections, said sections being hinged together and separated by die-scoring and die-cutting without substantial loss of material from the blank, said rear panel section being provided with a locking recess formed in the bottom of the U and said display panel section being provided with an ornamental projection corresponding in shape to said locking recess, and a locking projection upon said base section adapted to fold into said locking recess in the said rear section to lock the rack in display position. 60
